UNITED STATES PATENT OFFICE

149,935

DESIGN FOR A ROLY-POLY DOLL

Irwin Cohn, Leominster, Mass.

Application November 5, 1946, Serial No. 134,513

Term of patent 14 years

(Cl. D34—4)

To all whom it may concern:

Be it known that I, Irwin Cohn, a citizen of the United States, residing in Leominster, Massachusetts, have invented a new, original, and ornamental Design for a Roly-Poly Doll, of which the following is a specification, reference being had to the accompanying drawing, forming part thereof.

Fig. 1 is a top plan view of a roly-poly doll showing my new design;

Fig. 2 is a front elevational view of the doll shown in Fig. 1;

Fig. 3 is a side elevational view thereof.

I claim:

The ornamental design for a roly-poly doll, as shown.

IRWIN COHN.
